[57] CLAIM

The ornamental design for a combined bingo marker and caps, as shown and described.

DESCRIPTION

FIG. 1 is a side and end environmental perspective view of a combined bingo marker and caps showing my new design, the portion of the figure shown in broken lines representing a bingo card and user's hand and forming no part of the claimed design;

FIG. 2 is a side elevational view thereof with both caps installed, other elevational views being identical due to the symmetrical nature of the design;

FIG. 3 is a top plan view thereof with cap installed, the bottom plan view being identical;

FIG. 4 is a side elevational view thereof with one cap removed, other elevational views being identical due to the symmetrical nature of the design;

FIG. 5 is a top plan view thereof with one cap removed, the bottom plan view being identical to the view of FIG. 3;

FIG. 6 is a side and end perspective view thereof showing one cap separated from the remainder of the design; and,

FIG. 7 is an end view of a cap interior.
